TRANSISTOR IGNITION UNIT FOR AN AUTO-
MOBILE OR SIMILAR ARTICLE

Robert G. Van Houten, Grand Junction, Colo., assignor
to Delta Products, Inc., Grand Junction, Colo., a cor-
poration of Colorado

Filed Mar. 4, 1965, Ser. No. 84,096

Term of patent 14 years

(Cl. D26—13)

FIG. 1.

FIG. 2.

FIG. 3.

FIGURE 1 is a top plan view of a transistor ignition unit for an automobile or similar article, showing my new design;

FIGURE 2 is a side elevational view, the opposite side being substantially a mirror image thereof; and

FIGURE 3 is an end elevational view, the opposite end being substantially a mirror image thereof.

The bottom, not shown, is flat and unornamented.

I claim:

The ornamental design for a transistor ignition unit for an automobile or similar article, as shown and described.
